UNITED STATES PATENT OFFICE.

STANLEY J. PHILLIPS, OF MAYFIELD, PENNSYLVANIA.

COMBINATION TOOL.

Application filed January 29, 1923. Serial No. 615,677.

To all whom it may concern:

Be it known that I, STANLEY J. PHILLIPS, a citizen of the United States, residing at Mayfield, in the county of Lackawanna and 5 State of Pennsylvania, have invented new and useful Improvements in Combination Tools, of which the following is a specification.

This invention relates to combination 10 tools, and contemplates the provision of a device designed to be conveniently carried on the person of the user, and including a plurality of useful tools adapted to be folded compactly when not in use and easily extended and positioned for use when desired.

The nature and advantages of the invention will be better understood when the following detailed description is read in connection with the accompanying drawings, the 20 invention residing in the construction, combination and arrangement of parts as claimed.

In the drawings forming part of this application, like numerals of reference indicate similar parts in the several views, and wherein:

Figure 1 is a view in elevation of the device looking at one side of the tool.

Fig. 2 is a similar view looking at the 25 opposite side of the tool.

Fig. 3 is an edge elevation showing the parts in normal position.

Fig. 4 is an edge elevation showing the pivoted tool carrying member and one 30 end of the tool extended.

Fig. 5 is a view similar to Fig. 3 showing the can opener extended for use.

Fig. 6 is a vertical sectional view through the device on line 6—6 of Fig. 1 showing 35 the cork screw extended.

Fig. 7 is an enlarged transverse sectional view through the device taken on the line 7—7 of Fig. 1.

Fig. 8 is a sectional view taken on the 40 line 8—8 of Fig. 1.

Fig. 9 is a sectional view taken on the line 9—9 of Fig. 1.

Fig. 10 is a sectional view taken on the line 10—10 of Fig. 9.

Fig. 11 is an enlarged fragmentary view 45 partly in section showing a portion of the can opener.

Fig. 12 is an enlarged view in elevation

partly in section of the pivoted tool-carrying member and its associated parts.

55

Fig. 13 is a fragmentary view of one side of the device showing the guide slot.

Fig. 14 is a similar view of the lower part of the pivoted tool-carrying member.

Fig. 15 is a fragmentary view showing 60 the sliding tool-carrying member and its association with the frame.

Fig. 16 is a transverse sectional view through the sliding tool-carrying member and its associated parts.

65

Fig. 17 is a plan view of a portion of the device showing the sliding tool-carrying member and can opener.

The device forming the subject-matter of this invention embodies a frame-like member 70 which is substantially of inverted A formation as illustrated in Figs. 1 and 2. This frame is of a size to be conveniently carried in the pocket of the user, and the frame has associated therewith a plurality 75 of tools, for which use can be found from time to time.

The tools are associated with the frame in a manner to permit them to be folded compactly, and thus allow the device in its 80 entirety to be arranged in the pocket of the user, but these can also be quickly extended for use singly when desired. The frame

includes spaced side members 10 and is divided into upper and lower portions by 85 means of the transverse part of the frame indicated at 11. The members 10 are connected together at one end by means of an arched or curved portion 12. In the upper portion of the frame is a centrally disposed 90 bar 13, the latter being terminally connected to the cross member 11 and with the top portion 12 of the frame. This bar is provided as a support for the sliding tool-carrying member illustrated in Figs. 1 and 95 15. This member is indicated at 14 and is

of a cross-sectional configuration corresponding to the configuration of the bar 13. It will be noted however, in Fig. 15 that the opposed sides of the member 14 have 100 their upper edges inclined downwardly as at 17, and the lowermost extremities terminate to provide bearings for a pivot 18 as illustrated in Fig. 16. Projecting from the pivot 18 and arranged at opposite sides 105 of the bar 13 are parallel tools 19, the latter

having their corresponding free extremities pointed and curved in opposite directions as at 20. These tools are primarily intended for removing disk stoppers from milk bottles.

- The tools 19 project from one side of the pivot, while projecting from the opposite sides of the pivot is the tool 21 shaped to be utilized as a can opener. This tool is clearly illustrated in Figs. 1 and 17 and is shaped to penetrate the top of a can, and sever the top as the device in its entirety is moved in a circle about the can. A centering element forms part of the can opener, and is illustrated in several views, but more clearly in Fig. 11. This element is indicated at 22 and terminates to provide a hook-like extremity 23 which is adapted to penetrate the top of the can in the center and constituting a pivot about which the entire device is moved in a circular course for the purpose just stated. The centering element 22 slides through a transverse bore formed in the top portion 12 of the frame, and includes a head 24. The bore is also formed with a shoulder 25, between which and the head 24 is arranged a coiled spring 26. This spring normally holds the centering element retracted or in other words in the position shown in Fig. 11, but the element can be extended against the tension of the spring to the proper position for use in the manner just stated. The wall of the bore in which the element operates is provided with a groove 27, and the latter receives a lug 28 carried by the head 24, the lug preventing the centering element from turning within the bore as will be readily understood.
- The tools 19 and 21 are normally arranged in parallelism with the frame as illustrated in Fig. 15, and are held in this position by means of an extension 28' carried by one end of the pivot 18 at right angles thereto, and provided with a notch or opening 29 to receive the bulge portion 30 of a resilient element 31, one end of which is secured as at 32 to the adjacent side of the sliding tool-carrying member 14. The tools 19 and 21 move with the pivot as a unit to a position at a right angle which they normally occupy, when use of either of the tools is desired. These tools are automatically moved to active positions through the instrumentality of a coil spring 33 which encircles the pivot 18, and which is placed under tension when the tools 19 and 21 respectively are arranged in their normal positions. The tools just mentioned are manually returned to their normal positions and held in this position by means just described and including the spring 31. Consequently, when the spring 31 is depressed to separate it from the extension 28', the pivot is released, and the spring 33 is permitted to

function to automatically arrange the tools 19 and 21 respectively in active positions.

It will be noted upon inspection of Figs. 15 and 16 that the bar 13 is provided with longitudinal grooves 34 to receive projections 35 on the tool-carrying member 14, so that the latter is guided in its movements longitudinally of the bar.

The spaced members 10 of the frame are hollow for a portion of their length, and are open at the upper ends thereof. One of these members slidably receives a cigar lighter of well known construction and indicated at 36, in Fig. 8. This cigar lighter includes a wick 37 adapted to be ignited incident to the turning of the roughened wheel 39 against the spring-pressed carbondum element 40. In the other member 10 is arranged a hollow tubular member 41 provided with a head 42 of a size to snugly fit within the said member 10. The lower end of the tubular member 41 accommodates a cap 43 which is threaded on the member 41 and provided with a central opening 44, through which needles, pins or the like can be passed into the hollow tubular member 41. A light metallic cap-like covering 45 is then slipped over the end of the cap 43 to close the opening 44, and thus prevent the contents of the tubular member 41 from falling out of this member.

The cigar lighter 36 and the article just described are retained in the respective side members of the frame by a spring-pressed sliding bolt 46 adapted to be projected into a notch 47 as illustrated in Figs. 8 and 9. Each of these bolts is provided with means whereby it can be retracted to permit the particular article to be extracted from the frame, and this means includes a shaft or rod 47' which is mounted for rotation, either in the body of the cigar lighter or the head 42 of the article designed to accommodate the needles and pins. This shaft 47' is turned by means of a projection 48 which projects beyond the ends of the frame, forming part of the shaft 47'. Extending at a right angle from each shaft is a link 49 which has a slot and pin connection 50 with the lug 51 carried by each bolt 46. The articles with which these bolts are associated, are provided with pockets or the like 52 to afford sufficient space to permit the link 49 to move laterally, it being obvious that when the shaft is turned in one direction, the bolt is retracted, and when released, the bolt is extended to find its way into the notches or depressions 47. It may here be stated that in addition to receiving needles and pins, the diameter of this tubular member 41 is such as compared to the diameter of the side members of the frame in which it is positioned, that a spool of thread or the like can be slipped on the tubular member, and held thereon by means

of the cap 43. One side of the frame is provided with a toothed surface 39' against which the wheel 39 can be operated if desired.

5 Pivoted between the lower ends of the side members 10 of the frame is a tool-carrying member indicated at 53, and this member is adapted to fold between the side members 10 to lie flush with one side of the frame 10 when not in use. This member 53 is provided with lateral extensions 54 and 55 respectively, the latter projecting from the opposite longitudinal edges of the member 53, and is further equipped with an extension 56 which projects from one end of the member centrally thereof. The frame is recessed to receive these various extensions when a member is folded, which fact allows the member to lie flush with one side of the 20 member as stated. The extension 54 is designed for use in the capacity of a hammer head and is also formed to provide a claw as shown in Fig. 4 to permit of its use as a nail extractor. The extension 55 is shaped 25 to be used in the capacity of a bottle opener, while the extension 56 constitutes a screwdriver.

Pivoted upon the extension 55 is a disk 57 adapted to be used as a glass cutter. The 30 hammer head 54 is recessed as at 58, and adapted to fold into this recess is a reamer 59, the latter being pivoted as at 60 and capable of being extended to the position shown in Fig. 12 for use. The pivoted tool-carrying member 53 is also provided with lugs 61 which operate in arcuate-shaped slots 62 provided in the side members 10 of the frame, these slots limiting the pivotal movement of the member 53 in either direction. 40 The member 53 is also provided with a transverse bore 63 to accommodate a pivot which passes through openings 64 in the side members 10. Arranged upon the member 53 longitudinally thereof is a knife and 45 scissor grinder 65. A corkscrew 66 is also pivoted independently in the lower part of the frame and adapted to be arranged in the position shown in Fig. 2 when not in use, or extended at a right angle to the frame 50 for use as illustrated in Fig. 6.

While it is believed that from the foregoing description, the nature and advantages of the invention will be readily apparent, I desire to have it understood that I 55 do not limit myself to what is herein shown and described, and that such changes may be resorted to when desired as fall within the scope of what is claimed.

Having thus described the invention, I 60 claim:

1. A device of the character described,

comprising a frame having upper and lower open portions, a bar arranged centrally in the upper portion and constituting a support for a sliding tool-carrying member, a pivoted tool-carrying member arranged in the lower portion, angularly disposed extensions projecting from the pivoted tool-carrying member, and said frame having recesses to receive said extensions when the member is 65 folded.

2. In a device of the character described, a frame including spaced side members, and a transverse member connecting the sides and dividing the frame into upper and 75 lower open like portions, a cross-piece connecting the side members at one end, said side members being hollow for a portion of their length and adapted to receive movable tools, a support arranged in the upper portion for a slidable tool-carrying member, 80 and a pivoted tool-carrying member arranged in the lower portion.

3. A device of the character described, comprising a frame-like member, divided 85 into upper and lower open like portions, a centrally arranged bar in the upper portion, a tool-carrying member slidable on said bar, means for guiding said member, tools pivoted on said member and adapted to be arranged at a right angle to said bar for use, 90 and means for holding said tools normally in parallelism with the bar.

4. A device of the character described, comprising a frame divided into upper and 95 lower open like portions, a bar arranged centrally in the upper portion, a tool-carrying member slidable on said bar, a plurality of tools arranged in alignment, a pivot operating on said member and supporting said 100 tools, means for normally holding the tools in parallelism with said bar, and means for automatically operating the pivot to position the tools at a right angle to the bar for use.

5. A device of the character described, comprising a frame divided into upper and lower open like portions, a bar arranged centrally of the upper portion, a tool-carrying member slidable on said bar, a can 110 opener pivoted on said member and adapted to be arranged at a right angle to the bar for use, means for normally holding said tool parallel with the bar, a centering element forming part of the tool and slidable 115 in the frame and at a right angle thereto, said element terminating to provide a hook, and yieldable means for normally holding the element retracted.

In testimony whereof I affix my signature.

STANLEY J. PHILLIPS.
